US0D1012398S

(12) **United States Design Patent** (10) Patent No.: **US D1,012,398 S**
(45) Date of Patent: ** Jan. 23, 2024

(54) **PAINT CONTAINER HANDLE**

(71) Applicant: **Bercom International, LLC**,
Chanhassen, MN (US)

(72) Inventors: **Mark W. Bergman**, Minnetonka, MN
(US); **Jeffrey T. Given**, St. Paul, MN
(US); **Matthew V. Leyden**, St. Paul,
MN (US); **Jeffrey B. Waffensmith**,
North Oaks, MN (US)

(73) Assignee: **Bercom International, LLC**,
Chanhassen, MN (US)

(**) Term: **15 Years**

(21) Appl. No.: **29/819,061**

(22) Filed: **Dec. 13, 2021**

Related U.S. Application Data

(62) Division of application No. 29/711,216, filed on Oct.
29, 2019, now Pat. No. Des. 940,985, which is a
division of application No. 29/671,364, filed on Nov.
27, 2018, now Pat. No. Des. 867,708, which is a
division of application No. 29/610,298, filed on Jul.
11, 2017, now Pat. No. Des. 838,072, which is a
division of application No. 29/564,143, filed on May
11, 2016, now Pat. No. Des. 794,892.

CLAIM

The ornamental design for a paint container handle, as
shown and described.

DESCRIPTION

FIG. 1 is a top, right side and back perspective view of a
paint container handle;

FIG. 2 is a bottom, left side and back perspective view of
the container handle of FIG. 1;

FIG. 3 is a left side view of the container handle of FIG. 1;

FIG. 4 is a right side view of the container handle of FIG.
1;

FIG. 5 is a back view of the container handle of FIG. 1;

FIG. 6 is a front view of the container handle of FIG. 1;

FIG. 7 is a top view of the container handle of FIG. 1; and,

FIG. 8 is a bottom view of the container handle of FIG. 1.

The dashed lines in the FIGS. are for illustrative purposes

only and form no part of the claimed design.

1 Claim, 8 Drawing Sheets
